UNITED STATES PATENT OFFICE

PHILIP L. HAIMS, OF CLEVELAND, OHIO

HAIRPIN OR SIMILAR DEVICE

Application filed March 9, 1931. Serial No. 521,236.

My invention relates to hairpins or similar devices and particularly to a type utilizing spring force to clasp the hair between the legs of the pin.

In carrying my invention into practice it has been my purpose to provide a hairpin or clip of the type specified wherein the clasping action of the legs of the pin is effected by spring pressure and the release of such 10 clasping action accomplished by compression of the leg connecting portion of the pin.

I will describe my invention in the best forms known to me at present, but it will be 15 understood that the same is susceptible to further modifications in form without departing from the spirit of my invention.

In the drawings chosen to illustrate my invention, the scope whereof is set forth in 20 the appended claims.

Figures 1, 2, 3, 4 and 5 are side elevations of hairpins constructed in accordance with my invention, but illustrating respectively different adaptations thereof.

Figure 6 is a section on the line 6—6 of Figure 5.

Figure 7 is a side elevation of a modification of the form shown in Figures 5 and 6.

Figure 8 is a perspective view showing the 30 form illustrated in Figure 1 with the legs opened by pressure of the fingers of the hand upon the leg connecting portion of the pin.

Referring particularly to Figure 1, my improved hairpin is shown as formed from 35 a length of spring material shaped to provide legs 10 and 19 and a leg connecting portion formed by bending the length of material at 12, 13, 14, 15 and 16, to form arms 17 and 18, the complete leg connecting portion serving as a spring and exerting its force upon the legs 10 and 19 to normally maintain them 40 pressed together. To separate the legs it is only necessary to manually press the arms 17 and 18 of the leg connecting portion together against their normal spring action as clearly shown in Figure 8. In this form 45 of my invention I turn the free end of the leg 10 outwardly as at 11.

In the form illustrated in Figure 2, the 50 leg connecting portion is U-shape instead of

V-shape as in Figure 1, with the arms 23 and 24 of said portion normally parallel. In this form of my invention the leg 20 is corrugated as at 21, while both the leg 20 and leg 27 have their free ends turned outwardly as at 11^a and 29 respectively. 55

In the form shown in Figure 3 the leg connecting portion is similar to that of Figure 2, except for a slightly different shape at the base 31 thereof. In this form the leg 32 is provided with corrugations 33 which normally interfit with the corrugations 21 of the leg 20, while the free end of leg 32 is extended and turned in the same direction as the free end 11^a of leg 20. 60 65

In the form shown in Figure 4 the legs are indicated at 35 and 38 with a single corrugation 36 formed in the leg 35 and an opening 37 in leg 38 which is adapted to receive said corrugation when the pin is closed. 70

In the form shown in Figures 5 and 6 the leg 40 is curved transversely to form a half round surface which fits down over the similarly shaped leg 41, the leg connecting portion 42 being in the form of a loop. 75

Fig. 7 shows a modification which differs from figures 5 and 6 in that the legs have no transversely curved surfaces, the leg 45 having a plurality of corrugations 46 with a leg connecting portion 47 in the form of a loop 80 and the leg 48 having rounded indentations 49 positioned correspondingly to the corrugations 46 of the leg 45.

The various forms herein described may be interchanged or combined one with the other 85 so that the above described forms need not be strictly adhered to, and the device is capable of use either as a hairpin or as a clasp or clip for any other purpose, such as a tie holder or clasp. 90

I claim:

1. A hairpin or clip of spring material consisting of two legs and a leg connecting portion formed by successively bending the material upon itself to produce two normally spaced arms, said leg connecting portion exerting a spring action upon the legs to press them together and operable when the arms thereof are pressed toward each other to separate the legs, said arms being of substantially 95 100

equal length and having a loop portion there-between the forward end of which extends closely adjacent the rear ends of the legs and forms a fulcrum on which both legs swing open when the arms are pressed together.

- 6 2. A hairpin of spring material consisting of two legs one of which is provided with a corrugation and the other with an opening receiving the corrugation when the legs are
10 pressed together, and a leg connecting portion embodying two spaced arms, said leg connecting portion constantly exerting a spring action upon the legs to press them together and operable when the arms thereof are
15 pressed toward each other to separate the legs.

In testimony whereof, I do affix my signature.

PHILIP L. HAIMS.
